[57] **CLAIM**

The ornamental design for a ceiling fan motor housing, as shown and described.

DESCRIPTION

FIG. 1 is a top plan view of a ceiling fan motor housing showing our new design;

FIG. 2 is a side elevation view thereof, the opposite side being a mirror image of that shown; and,

FIG. 3 is a bottom plan view thereof.

The shaft has been broken away in FIG. 2 at the top and bottom ends to indicate indeterminate length.
